UNITED STATES PATENT OFFICE.

EDWARD M. BALL, OF HATLEY, ASSIGNOR TO SAMUEL CLEVELAND, OF NORTH COATICOOK, QUEBEC, CANADA.

STOVE-PIPE THREADER AND BEADER.

SPECIFICATION forming part of Letters Patent No. 244,420, dated July 19, 1881.

Application filed June 1, 1881. (No model.)

To all whom it may concern:

Be it known that I, EDWARD M. BALL, a citizen of Canada, residing at Hatley, in the county of Stanstead and Province of Quebec, have invented certain new and useful Improvements in Stove-Pipe Threaders and Beaders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

Figure 1 is a side elevation of a machine embodying my invention. Fig. 2 is an elevation showing that end which is at the left in Fig. 1. Fig. 3 is a vertical section of the same, showing those parts which are to the right in Fig. 1. Fig. 4 is a rear-end view of the hand-crank and operating-gears; and Fig. 5 is a longitudinal central sectional view.

This invention relates to improvements in stove-pipe machines, and has for its object the forming of a screw-thread and forming the usual bead at one and the same time on the ends of stove-pipe; means for giving the requisite pitch to such screw-thread; means whereby the beading-rolls are maintained at the same relative position with that of the frame of the machine; means for permitting the seams of the pipe to pass readily between the beading and screw-threading rolls; in the face-plate and its adjustment devices, whereby the distance of the bead from the ends of the pipes may be varied; and means whereby the power of the hand on the hand-crank is greatly augmented.

The nature of the invention consists of the devices substantially as hereinafter more fully set forth and claimed.

In the accompanying drawings, A is the frame of the machine, which supports the shafts B and C, a portion of whose rear ends is screw-threaded, and which work in correspondingly screw-threaded bearings in the rear vertical portion of the frame A. One of these shafts has a right-hand thread, the other a left-hand thread, the drawings representing the shaft B provided with right-hand thread.

The forward vertical portion of the frame A is bifurcated, as shown in Fig. 3, in which the boxes q r are fitted. The box r rests in the bottom of the bifurcation, while the box q is separated from the box r by means of a spring, 55 s. Lateral motion of the said boxes is prevented by lateral flanges on each box, which overlap the edges of the frame A, which thus serve as ways for the boxes.

Superimposed on the box q, and lying between it and the follower g, is a spring, h, preferably of rubber, which may be compressed by means of the hand-screw f, screw-threaded and working in the cap t. The lower extremity of this hand-screw bears on the top face of 65 the follower g.

Securely fastened to the shaft B, immediately forward of the frame A, is the male screw-threading roll l. Just below this, and similarly secured to the shaft C, is the female 70 screw-threading roll m. The ends of the shafts B and C, which project forward of the rolls l m, are provided with feather-keys p p', which fit in keyways in the beading-rolls j k, in order to compel the said rolls to revolve when 75 the shafts B and C are put in motion. By means of spring-bars n o, which hook into the circumferential grooves near the forward ends of the beading-rolls j k, the said beading-rolls are maintained at the same distance from the 80 frame A, the shafts B and C sliding freely through when the machine is at work.

The face-plate D is made adjustable by means of its supporting-screws i i', projecting through holes in the frame A for that purpose. The 85 said screws are provided with nuts, two to each, which are screwed against the sides of that portion of the frame A, as shown in Fig. 1, thus making it possible to adjust the face-plate D at the required distance from the frame 90 A, and at the desired angle with the same.

To cause the shafts B and C to revolve at the same relative rate of speed, they are provided with gear-wheels a b, of equal diameters and securely fastened to their respective shafts, 95 and to prevent their working relations from being injuriously affected by the varying distances of the forward end of the shaft B from the shaft C in adjusting and working the same, the gear-wheels a b are placed as far to the 100

rear as possible, and yet have them within the vertical portions of the frame A.

The rear extremity of the shaft B carries, loosely mounted thereon, a pinion, c, to which 5 the hand-crank e is attached in any secure manner. This pinion gears with a larger wheel, d, keyed or otherwise fastened to the shaft C. It will thus be seen that the power of the hand on the crank e will be augmented in proportion to the difference in the sizes of the gears c d.

When screw-threading and beading stove-pipe it is placed on the lower rolls, as shown in Fig. 1, E representing a longitudinal section of pipe being operated on. The hand-screw f is then screwed down until the pressure is sufficient to properly groove or thread the pipe, when the handle e is turned in the direction of the arrow in Fig. 4, which will 20 give a right-handed thread on the pipe. In passing seams of the pipe between the rolls the spring h will yield sufficiently to prevent damage to the machine.

For left-hand screw-threading, the pipe is 25 placed on the upper rolls, when the operation of the machine will be similar in all respects.

When it is desired to screw-thread pipe without beading, the beading-rolls may be removed.

When it is desired to bead pipe without

screw-threading, the screw-threading rolls may 30 be removed.

Having thus described my invention, I claim as new and desire to secure by Letters Patent—

1. The combination of the frame A, shafts B C, provided with threading-rolls and moving 35 in screw-threaded bearings, and gearing a b c d, the gear c revolving loosely around its shaft, as and for the purpose set forth.

2. The circumferentially-grooved beading-rolls j k, in combination with shafts B C, bars 40 n o, and frame A, as and for the purpose set forth.

3. The circumferentially-grooved beading-rolls j k, in combination with shafts B C, bars 45 n o, adjustable face-plate, and frame A, substantially as shown and described.

4. The combination of the screw-threaded shafts B C, moving in screw-threaded bearings, rolls j k and l m, adjustable plate D, the shaft B, held down at its outer end by a yielding bearing, and means for operating said shafts B C, as and for the purpose set forth. 50

In testimony whereof I affix my signature in presence of two witnesses.

EDWARD M. BALL.
